ABSTRACT OF THE DISCLOSURE

A coin freed ball storage system for a table for playing games such as pool and snooker for which there is used one or more cue balls and a set of object balls, the system comprising a path for object balls from the pockets of the table to a return receptacle, a displaceable barrier in the path normally closed to obstruct the passage of balls to store object balls as they are pocketed in an inaccessible position within the table, means freed by coin insertion for opening the barrier, and means which responds to the passage of the object ball first pocketed to restore the barrier to closed condition.

This invention relates to automatic coin controlled pool tables and more particularly to control systems therefor for releasing from storage the object balls in response to coin insertion.

The expression "pool table" wherever used herein is intended to refer to the form of table commonly used with a set of balls composed of one or more cue balls and a number of object balls of one or more groups, such as in the games of snooker and pool.

A requirement for the game of pool which the table of the invention is designed to provide is the return of the cue ball after pocketing at all times during a game while the object balls, usually numbered from 1 to 15 are no longer required during the game after they have been pocketed. A similar requirement exists in the game of snooker in so far as the cue ball and red object balls are concerned. Disregarding the so-called coloured balls of this latter game, therefore, a similar provision in the table will suffice for both games.

It is the object of this invention to provide means in a pool table for automatically controlling firstly the release of all object balls in response to coin insertion and storage of all object balls after pocketing.

It is also an object of the invention to provide means for achieving this result which is efficient, of simple construction and capable of operating on low power consumption from a battery source.

In a general form the invention provides a coin freed ball storage system for releasably storing in an inaccessible position within a pool table object balls as they are pocketed during a game, said system comprising a path for passage of object balls from pockets to a return receptacle on the table, a displaceable barrier in the said path normally obstructing the passage of balls, means freed by coin insertion for removing the barrier, and means responsive to passage of the first object ball pocketed in the game to restore the barrier.

The features of the invention will become clearer from an understanding of the following description with reference to the accompanying drawings, in which:

FIG. 1 illustrates by schematic diagram the necessary components for one embodiment of a control system of the invention;

FIG. 2 shows one form of releasable ball barrier which may be used with the circuitry of FIG. 1; and

2

FIG. 3 shows schematically another embodiment capable of substitution for the control system of FIGS. 1 and 2.

With reference to FIGS. 1 and 2 of the drawings, there is shown a motor M which will be energized from the battery source upon closure of either contact *r1* or *m2*. FIG. 2 shows a ball passage tube 4 which will be located in the path of object balls passing from the pockets of a pool table to a return tray or other receptacle on the pool table which is accessible to the players. The ball passage tube 4 is itself positioned within the table in a location inaccessible to the players. A shaft 5 of the motor M carries at its outer end a pair of juxtaposed cylindrical cams M1 and M2 provided with registering notches 6 and 7 at one portion of their peripheries. The cam M2 is provided with a second peripheral notch 8 approximately diametrically opposite its notch 7. The end of the shaft 5 carries an eccentric vane 9 having its extending portion 10 protruding transversely through a circumferential slot 11 in the wall of the ball passage tube 4. Respective actuators 12 and 13 for microswitches (not shown) are mounted with respect to the cams M1 and M2 so that with rotation of the shaft 5 they ride over the periphery of the two cams M1 and M2 in which condition contacts *m1* and *m2* are moved to their off-normal conditions. These contacts restore whenever the actuators 12 and 13 engage in their respective notches 6, 7 and 8.

Any suitable means may be included in the table to ensure that the object balls in their passage from the pockets of the table to the return tray pass via the ball passage tube 4. For example, the mechanical construction of the table may comprise the provision of inwardly sloping platforms to receive all balls entering the pockets of the table to direct them inwardly to a central location. Beneath the central location may be provided discriminating inclined rails spaced so as to retain the object balls thereon while permitting the fall of the cue ball of smaller diameter than the object balls, through the rails into a passageway leading directly to the return tray. The ball passage tube 4, which is also inclined downwardly communicates with the lower end of the discriminating rails to receive the object balls therefrom and at its lower end communicates with the receiving tray.

It will be seen, therefore, that the portion 10 of the vane 9 protruding into the ball passage tube 4 will serve as a barrier to balls rolling down the tube 4. When the shaft 5 is rotated, however, the protruding portion 10 of the vane 9 is moved out of the tube 4 to permit free passage of the object balls to the return tray.

For the game of snooker the coloured object balls, i.e., those additional to the red balls and cue ball, will be of a different diameter to the red object balls to ensure their availability for "respotting" while red balls remain on the table, or, when a foul stroke has been played. By providing the coloured object balls with a diameter different from all other balls they may be segregated within the table for special handling such as for non-return after a stage of the game has been completed.

A control system for the releasable storage of object balls, such as the numbered balls in pool or the red balls in snooker, is shown in FIG. 1 where it will be seen that operation of contacts *cs* closes the circuit from the battery to the relay R. The contacts *cs* are associated with a microswitch (not shown) which is operated momentarily upon the insertion of an appropriate coin by a prospective player. As soon as relay R operates, a holding circuit is provided through its contacts *r2* and the normally closed contacts *m2*. Contacts *r1* also close and the motor M commences to rotate. As explained above, contacts *m1* and *m2* change-over to an off-normal condition so that the

former closes and prepares an additional energizing circuit for the relay R, and the latter contacts hold the motor M energized so that it continues to rotate. In this position of contacts m2 the energizing circuit for relay R is broken. When the motor has completed approximately half a revolution contacts m2 restore to normal when the notch 8 in the cam M2 is engaged by the actuator 13 of the respective microswitch. The motor M then ceases to operate and the circuit remains at its off-normal rest position with the protruding portion 10 of the vane 9 out of register with the slot 11 of the tube 4. The object balls stored in the tube are then free to pass to the return tray for use by the players.

As the game progresses one of the object balls will ultimately be pocketed and pass to the discriminating rails and thence to the ball passage tube 4. An actuating lever for a microswitch (not shown) is contacted by each object ball passing to the tube 4 to cause momentary closure of contacts rs. Upon the first operation of contacts rs the relay R is again energized from the battery over contacts rs and m1, now closed, and contacts m2, now restored to normal. Again the hold circuit for the relay R is provided by contacts r2 while the motor M is energized by closing of contacts r1. The motor will continue to rotate for the remainder of a single revolution with contacts m2 now in an off-normal condition, until the actuators 12 and 13 again engage in the notches 6 and 7 of the cams m1 and m2. The motor then will cease to operate through restoration of contacts m2 and the protruding portion 10 of the vane 9 will again form a barrier to the passage of balls along the tube 4. Therefore, although the cue ball is continually returned if pocketed, the object balls which are pocketed are stored in the ball passage tube 4 until a further coin is inserted into the table mechanism.

By the use of the above described circuit a very low drain and low voltage potential is required from the battery source. By appropriate choice of relay and motor a conveniently sized battery of 3.6 v. would supply the power needs for the table for a long period of time.

An alternative form of control system is shown in FIG. 3 which in place of the motor M employs a pair of solenoids. Solenoid SA is provided with two contacts sa1 and sa2 and its plunger is attached to a spring returned slide 14 retractable from a transverse slot in the ball passage tube 4. The second solenoid SB is provided with a single contact sb1 and its plunger is engageable with an abutment on the slide 14 when it is in a retracted position to hold the slide in this position until the solenoid SB is energized.

The circuit of FIG. 3 functions as follows.

Closure of the coin switch contacts cs operates the relay R which locks-on over its contacts r2. Contacts r1 then energize solenoid SA to retract the slide 14 and allow the stored object balls to pass from the tube 4 into the return tray on the table. Contacts sa1 changeover and hold solenoid SA energized. When the object ball closes contacts rs solenoid SB operates over these contacts and now closed contacts sa2 to retract its plunger and release the slide 14. Through its contacts sb1 which now open, solenoid SA releases and the slide 14 returns under spring action to its barrier position to the balls in the tube 4. The drain of the battery source with this later form of control system would in most cases exceed that of the motor M of the previous embodiment. Nevertheless, the circuit has useful application and the load on the battery can be maintained reasonably low by appropriate choice of solenoids.

Two forms of control systems have been described in

the foregoing passages but it is to be understood that other forms are also feasible within the scope of this invention.

What I claim is:

- 5 1. A coin freed ball storage system for releasably storing in an inaccessible position within a pool table object balls as they are pocketed during a game, said system comprising a path for passage of object balls from pockets on the table to a return receptacle, a displaceable barrier in the said path normally obstructing the passage of balls, means freed by coin insertion for removing the barrier, and means responsive to passage of the first object ball pocketed in the game to restore the barrier.
- 10 2. A coin freed ball storage system according to claim 1, wherein said means for removing the barrier is energized under the control of a relay which is operated upon coin insertion and released when said means for removing the barrier is energized.
- 15 3. A coin freed ball storage system according to claim 2, wherein a pair of contacts are operated upon coin insertion and the relay is serially connected therewith and in parallel with said means for removing the barrier.
- 20 4. A coin freed ball storage system according to claim 3, wherein said means for removing the barrier has electrical contacts which disconnect the relay from power when said means for removing the barrier is energized.
- 25 5. A coin freed ball storage system according to claim 1, wherein the barrier is a vane carried upon a shaft rotatable by an electric motor, said vane normally protruding into a ball tube forming part of the said path for object balls and being withdrawn therefrom upon rotation of the shaft.
- 30 6. A coin freed ball storage system according to claim 5, wherein a cam is also carried upon the shaft and contacts are provided whose operation is controlled by said cam, said contacts stopping operation of the motor when the vane is withdrawn from the tube, and said motor being restarted to return the vane to normal position whereby the barrier is restored.
- 35 7. A coin freed ball storage system for releasably storing in an inaccessible position within a pool table object balls as they are pocketed during a game, said system comprising a path for passage of object balls from pockets on the table to a return receptacle, a displaceable barrier in the said path normally obstructing the passage of balls, means freed by coin insertion for removing the barrier, and means responsive to passage of the first object ball pocketed in the game to restore the barrier, a solenoid having a plunger and being energized by said removing means for the barrier, and a ball tube forming part of the said path for object balls, said barrier being a slide carried by said plunger and normally protruding into said ball tube.
- 40 8. A coin freed ball storage system according to claim 7, wherein a second solenoid is provided having a plunger which in extended position locks the slide in an off-normal position, said second solenoid being operated by said barrier restoring means to release said slide.
